J. BUSSANICH

MILK CAN PERFORATOR AND PROTECTOR

Filed May 20, 1922

By Attorney
Richard J. Cook

UNITED STATES PATENT OFFICE.

JOHN BUSSANICH, OF DOCKTON, WASHINGTON.

MILK-CAN PERFORATOR AND PROTECTOR.

Application filed May 20, 1922. Serial No. 562,384.

To all whom it may concern:

Be it known that I, JOHN BUSSANICH, a citizen of the United States, and a resident of Dockton, Vashon Island, county of King, 5 and State of Washington, have invented certain new and useful Improvements in Milk-Can Perforators and Protectors, of which the following is a specification.

This invention relates to improvements in 10 milk can perforators and protectors, and more particularly to devices of that character that are applicable to cans wherein condensed milk is sold.

The object of my invention is to provide 15 a device of the above character which may be easily and quickly applied and secured to the can, and which comprises means whereby the can may be perforated so as to provide an air inlet and a pouring outlet, and which 20 embodies means whereby the openings may be protected at all times and at the same time kept open and clean.

Other objects of the invention reside in 25 the details of construction of the parts embodied in the device, and in their combination and mode of operation.

In accomplishing these and other objects 30 of the invention, I have provided the improved details of construction, the preferred forms of which are illustrated in the accompanying drawings, wherein—

Figure 1 is a perspective view of a can 35 perforating and protecting device embodied by the present invention, as applied to a can.

Figure 2 is a top view of the same.

Figure 3 is a front view of the device, showing the perforating arms in raised position to uncover the can openings.

Figure 4 is a horizontal, sectional view 40 through the device, showing the construction and mounting of the perforating arms.

Figure 5 is a side view of the device.

Referring more in detail to the several 45 views of the drawings—

1 designates what may be an ordinary type of can wherein condensed milk, or the like, may be contained and over the upper end wall 2 of which a perforating and protecting device, embodied by the present invention, is 50 applied. This device comprises a base, or clamping plate 3 provided at one end with spaced hooks 4 and 5 and engaging one side edge of the can, and at its other end has a hook 6 for engaging the opposite side edge.

55 Centrally of the plate is an upwardly ex-

tended loop 7, whereby a desired resiliency is provided which permits the hooks to be drawn tightly against the can walls to hold the plate tightly in functional position. The means whereby this tightening action is effected comprises a pin 9, see Figure 5, that is extended across the lower portion of the loop and which has a head 10 at one end and a block 11 at its opposite end to which is pivotally fixed a lever 12 having an eccentrically formed head 13 which operates against that side of the loop, when the lever is pressed downwardly from position as shown in Figure 4 to position shown in Figure 1, to draw the loop together and thereby 60 tighten the hooks against the can.

Pivots mounted at their inner ends on the pin 9, between the vertical portions of the loop 7, are oppositely extending arms 15 and 16, each of which at its outer end carries a cam perforating pin 17. Mounted on the upper ends of these pins are pads 18 against which pressure may be applied to press the pointed lower ends of the pins through the can end. Also mounted about 75 the lower portions of the pins, are inverted, cup shaped pads 19 whereby the openings formed in the can end are protected against the collection of dirt thereabout, and from insects, and are sealed against possible leakage.

It is preferred that the arms 15 and 16 be made by bending strips of metal at the centers about the pins 17, as shown in Figure 5, and extending rivets 22 therethrough next 80 to the pins, then spreading the end portions of the arms apart so as to add strength and rigidity to the construction.

In order that these arms 15 and 16 may be easily raised with the same hand in which 85 the can is held while its contents is being poured out, I have provided a lever 25 having a portion 26 depending along the side wall of the can, as shown in Figures 1 and 4, and having a horizontal arm 27 extended 100 to a point directly above the loop 7. This lever is mounted pivotally upon a standard 28 formed at one end of the plate 3 between the hooked portions 4 and 5.

Pivots fixed to the end of the lever arm 105 27 are two links 28 and 29 which, at their lower ends, are pivotally connected respectively to the perforating arms 15 and 16 so that, when the lever handle 26 is pressed against the can wall, the arms 15 and 16 will 110

be raised and the perforations formed by the pressing of the pins 17 through the can end, will be uncovered.

A coiled spring 30 is fixed at its opposite ends to the lever arm 27 and to the plate 3 to yieldingly retain the perforating arms in lowered position and the pads 19 tightly against the can.

In order that the clamp plate will release itself from the can when the clamping lever 12 is thrown upwardly, I have placed a coiled compression spring 35 between the sides of the loop 7 and about the pin 9 which acts to spread the loop and extend the length 15 of the plate between its hooked ends.

Assuming that the device is so constructed, to use the same it is placed over the end of a can and then the lever 12 is pressed downwardly to draw the loop 7 together and tighten the hooks at opposite ends of the plate against the can edges. Pressure is then applied against the pads 18 whereby the lower pointed ends of the pins 17 will be pressed through the can end 25 wall at diametrically opposite points thereof. The tension of the spring 30, pulling downwardly on the lever 27, through the connecting links 28 and 29, retains the arms 15 and 16 tightly against the can so that 30 the pins normally retain the perforations closed, and the pads 19 cover the can about the perforations.

To pour milk from the can, the can is grasped so that the lever arm 26 may be 35 pressed against the can side wall, and this will lift the lever arm 27 and arms 15 and 16 to cause the perforations to be uncovered. The milk can then be poured from one opening while air is admitted into the can 40 through the other.

When the lever 26 is released, the spring 30 moves the parts back to normal position.

To remove the device from the can, the lever 12 is moved upwardly so that its eccentric head 13 is disengaged from the side 45 portion of loop 7 and spring 35 causes the loop to be spread apart and the hooks at the ends of the plate released from the can.

Having thus described my invention, 50 what I claim as new therein and desire to secure by Letters-Patent, is:

1. A device of the class described, comprising a plate adapted to be clamped upon the end of a can, arms having ends pivotally fixed to the plate and extending toward opposite edges of the can, pins mounted in the ends of said arms for perforating the can end, a lever mounted on the plate having operative connection with the said arms 55 whereby the latter may be lifted to remove the perforating pins from the can end and a spring connected with the lever and with the clamping plate whereby the perforating pins are yieldably retained within the 60 can perforations.

2. A device of the class described, comprising a plate adapted to be clamped across the end of a can, arms having ends pivotally fixed to the plate and extending toward opposite edges of the can, pins 70 mounted at the ends of said arms having sharpened ends adapted to be pressed through the can wall, pads mounted on the upper ends of said pins, pads mounted about the lower ends of the pins for covering the 75 can about the perforations, a standard formed at one end of the clamping plate and a lever mounted on said standard, having one end operatively connected with the said arms and a portion depending along 80 the side of the can that may be depressed to lift the said arms to uncover the perforations.

3. A device of the character described, comprising a clamping plate adapted to be 85 applied to the end of a can and having hooks at its opposite ends engageable with the opposite edges of the can; said plate having a loop formed centrally thereof, a pin extended across the loop, an eccentrically mounted lever fixed to one end of the pin and operable to close the loop to tighten the hooks against the can, a pair of arms having their inner ends mounted on said pin, perforating pins mounted at the outer 95 ends of said arms, a lever mounted on the plate, links connecting one end of the lever with the said arms and a handle portion for the lever that may be depressed to raise the said arms from the can end. 100

4. A device of the character described, comprising a plate adapted to be applied to the end of a can, having hooks at its opposite ends for engaging opposite edges of the can and having a standard at one end 105 and a downwardly opening loop at its center, a tightening pin extended across the open end of the loop, an eccentric lever fixed to one end of the pin operable to close the loop to tighten the hook of the plate against the can, a pair of perforating arms having their inner ends pivotally mounted on said pin, perforating pins mounted at the outer ends of said arms and adapted to be pressed through the end of the can, pads mounted upon the upper ends of the pins, pads mounted about the pointed ends for covering the can about the perforations, a lever mounted upon the standard, having a handle portion depending along the side of the can 115 and a horizontal portion extended about the loop, links fixed to the end of said horizontal portion and to the perforating arms and a spring fixed to the lever and to the plate whereby the arms are retained normally against the can. 120

Signed at Seattle, Washington, this 15th day of May, 1922.

JOHN BUSSANICH.
